INFANT'S SHOE

Arthur P. Williams, St. Louis, Mo.

Application January 26, 1950, Serial No. 7,490

Term of patent 3½ years

(Cl. D7—7)

To all whom it may concern:

Be it known that I, Arthur P. Williams, a citizen of the United States, residing in the city of St. Louis, State of Missouri, have invented a new, original, and ornamental Design for an Infant's Shoe, of which the following is a specification, reference being had to the accompanying drawing, forming a part thereof.

In the drawing:

Fig. 1 is a top or plan view;

Fig. 2 is a front elevational view;

Fig. 3 is a side elevational view of the right side of the shoe, and

Fig. 4 is a side elevational view of the left side of the shoe, each view showing an infant's shoe of my new design.

The ribbon is shown in fragmentary condition to indicate indeterminate length and the drawing shaded to indicate contrast in colors in part.

I claim:

The ornamental design for an infant's shoe, substantially as shown and described.

ARTHUR P. WILLIAMS.
